JULES PELIMLIN, OF MULHOUSE, FRANCE

DRAWING DEVICE FOR SPINNING MULES, SPINNING FRAMES, AND PREPARATORY MACHINES

Application filed February 15, 1927, Serial No. 168,480, and in France February 17, 1926.

The present invention relates to improved sliver or roving drawing devices devised for the drawing effected by spinning mules, jennies, spinning frames, and the like, as also by preparatory machines and for drawing frames.

Two requirements are to be complied with whenever a drawing operation is to be performed: (1) the least possible distance should be kept between the clasping point of the drawing rollers and the clasp, (2) the pressure exerted upon the sliver or roving by the clasp of the intermediate rollers should be slight so as to permit slip and drawing of the fibre at such point.

These requirements have been, to a certain extent, complied with in the devices already known, a number of which to gain the first requirement make use of an upper clasping roller of a comparatively small diameter resting upon a lower roller with a fluted surface, while others to gain the second requirement resort to the use of one or more sleeves on the order of small endless aprons. The small clasping rollers are advantageous in that they are very simply devised, but they are objectionable in that their work is neither perfect nor reliable. As to the use of endless aprons, they are fairly effective but are rather complicated, very expensive in respect of both cost and upkeep, and, therefore, do not provide for economical work.

The subject-matter of this present invention provides for proper drawing by reason that the floating roller, i. e. the upper one of the two intermediate clasping rollers comprised in a series of pairs of rollers, has been equipped with a sleeve-like body having a sufficient thickness to provide a great resiliency and flexibility. As a result of the weight of said floating roller (with the addition, if ever necessary, of an extra weight) the sleeve-like body resiliently presses against the lower roller and is so deformed as to conform to the surface of the same and cover a considerable part of its circumferential surface in the nature of a belt grip while yet preserving the advantage of a roller grip, the point at which it releases the sliver or roving being brought as near as possible to the

clasping point of the drawing rollers. Moreover, this arrangement provides for clasping the sliver upon a comparatively great length, though requiring for proper clasping action but a slight pressure owing to the great resiliency and flexibility of the yielding body of the floating roller, whereby only a restricted portion of the total pressure is imparted to the sliver.

In the accompanying drawing there is shown, by way of an example, one embodiment of the present invention.

In the drawing:

Figure 1 is a diagrammatic view of the new device combined in a series of drawing rollers;

Fig. 2 is a view in front elevation and partly in section of the floater, i. e. the upper intermediate clasping roller; and

Fig. 3 is a sectional view of the intermediate pair of clasping rollers, showing the yielding, sleeve-like body of the floater furnished with a covering of thin and flexible skin.

In the embodiment of the invention illustrated by Fig. 1, the arrangement comprises, between the feed rollers A¹ and A² and the delivery rollers B¹ and B², otherwise known as drawing rollers, the intermediate pair of rollers comprising a fluted roller C and a floater D. The distance between these intermediate rollers and the drawing rollers is as short as is practicable, and is, in any case, slightly less than the average length of the fibre to be spun.

The floating roller D comprises a metal core a which has been equipped with a sleeve-like body b of substantial thickness and having great resiliency. In order to provide for fulfillment of so essential a condition (great resiliency and flexibility of floater D) the sleeve b will be made of some very resilient and yielding substance, such as india-rubber, pure Pará rubber or spongy rubber, or of very soft felt, or the like. It has been found in practice that the required resiliency and flexibility or elastic suppleness of the floater D to enable it to deform sufficiently to obtain a belt-like grip on the lower intermediate roller C, is best secured by employ-

ing a sleeve having a cellular internal structure throughout its thickness. One example is sponge rubber named above. In some cases, such sleeve will be covered with a protecting sheath of some thin and flexible skin, as indicated by b^1 , Fig. 3. As a result of its own weight (increased, if need be, by the addition of a weight c hanging from a hook d) such sleeve-like body b will be modified in its external contour so as to conform to the surface of the lower roller C thus embracing this roller upon a fairly long arc of its circumferential surface (Figs. 1 and 3). The pressure exerted by the roller D upon the sliver or roving E and the length of its circumferential contact with the roller C can be modified by altering the value of the weight c .

To limit the pressure exerted by the roller upon the sliver or roving the shaft a need only have a step-up part e of a predetermined diameter; indeed, any increase in the value of the weight c will result in an increase of the pressure upon the sliver or roving, and will correspondingly increase deformation of the sleeve-like body b , only until the step-up part e comes to rest upon the lower intermediate roller C , whereupon the pressure upon the sleeve can only increase together with an increase in the thickness of said sliver or roving.

Briefly summarized, the present invention is characterized by the use of an upper roller D , of the intermediate pair of clasping rollers, comprising a body of readily deformable material having a cellular internal construction of substantial thickness. This body, as shown in Figs. 1 and 3, is deformed by pressure against the periphery of the hard, co-acting lower intermediate roller C so as to conform to its circumferential surface like a belt throughout a considerable arc, extending both rearward and forward of the plane in which the axes of the two rollers D and C lie. The forward extent of said arc around said roller C is to a point relatively close to the nip of the forward pair of drawing rollers. It will be perceived that the sliver or roving E , in passing between the intermediate rollers D and C on its way from the feeding rollers A^1 and A^2 to the drawing rollers B^1 and B^2 , is confined and controlled through a material part of its travel to the pair of drawing rollers, between extensive surface portions of the intermediate rollers which are continuously in contact with each other. It will further be perceived that the extended control of the sliver or roving, by means of the peculiar shaping of the deformable floating roller D to the contour of the lower roller C , not only provides for the carrying-forward of the sliver or roving throughout a considerable portion of the interval between the feeding-rollers, and the drawing rollers but, by virtue of the control

thus exercised over the sliver being continued to a point close to the nip of the drawing-rollers, the fibres of the sliver or roving are payed out evenly to the drawing-rollers and the "fly" or short fibres are prevented from being drawn forward in variable quantity, whereby unevenness in the drawn sliver or roving as delivered by the rollers B^1 , B^2 , is avoided, even when the sliver or roving is composed of fibres of unequal length.

Having thus described the preferred form of my invention, what I claim as new and desire to secure by Letters Patent is:—

1. An upper intermediate roller for drawing devices for machines of the class described comprising a cylindrical core portion and a flexible resilient cover, said cover being characterized by its considerable thickness, great resiliency and flexibility, so that by pressing on the bottom roller it embraces the latter upon a comparatively large part of its peripheral surface, the cylindrical core portion being provided on each side of the cover with a step-up part of such a diameter as to limit the pressure of the top roller upon the sliver or roving within a predetermined maximum, independently of the amount of pressure.

2. A cover for upper intermediate rollers of drawing devices comprising a cylindrical sleeve of very soft elastic material and of considerable thickness adapted to embrace the bottom roller upon a comparatively large part of its circumferential surface, and having a protecting sheath of soft and flexible skin.

3. Drawing devices for machines of the class described having, in combination, co-acting feed rollers, coacting drawing rollers, and an upper intermediate roller having a deformable covering adapted when pressed against a coacting lower intermediate member to spread over a comparatively large area of the latter's surface, to obtain a belt-like engagement of the sliver and to extend its control of the sliver a substantial distance in the direction of extent of said sliver and consequently toward the nip of the drawing rollers.

4. Drawing devices for machines of the class described having, in combination, a pair of feed rollers, a pair of drawing rollers, and an intermediate pair of clasping rollers, one roller of said intermediate pair comprising a body of substantial thickness of readily deformable material with substantial circumferential arcs of said thickness displaceable bodily around and conforming to the convexity of the coacting roller by pressure against the latter, with the resulting concavity produced in said body embracing the circumferential surface of said coacting roller throughout a considerable arc, extending forward of the plane in which the axes of the said intermediate pairs of rollers lie and

continuing to a point relatively close to the
5 nip of the drawing-rollers, whereby a con-
siderable length of the sliver is confined and
controlled throughout a material part of its
travel from the feed rollers to the drawing-
rollers between relatively extensive surfaces
continuously in clasping contact with said
considerable length.

5. In a device of the class described for
10 drawing slivers or rovings, an upper clasping
roller comprising a rigid core having mount-
ed thereon a sleeve-like cellular body of sub-
stantial thickness and of such great resiliency
as to be deformable through a substantial
15 depth of its thickness when pressed against
a coacting lower clasping roller thus to con-
tact with a relatively long arc of the surface
of said lower roller.

6. An upper intermediate roller for draw-
20 ing frames having a rigid core and a cover
therefor comprising a resilient cylindrical
sleeve having a wall of considerable thick-
ness as compared to the diameter of said core,
said wall internally being broken into a plu-
25 rality of cells but externally presenting a
solid circumferential surface.

7. A floater roller for devices of the char-
acter described comprising a substantial body
of resilient material characterized by in-
30 ternal air cells.

8. In a sliver or roving drawing device, an
upper intermediate roller comprising a sleeve
of sponge rubber.

In testimony whereof I signed hereunto my
35 name.

JULES PFLIMLIN.
